UNITED STATES PATENT OFFICE.

JOSEPH HUTT AND GEORGE H. BIRD, OF COVENTRY, ENGLAND, ASSIGNORS TO GENERAL ELECTRIC COMPANY, A CORPORATION OF NEW YORK.

ACOUSTIC DEVICE.

Application filed May 11, 1926, Serial No. 108,355, and in Great Britain June 8, 1925.

The invention relates to telephone receivers and transmitters, loud speaking telephones, microphones and the like apparatus in which a vibratory diaphragm is excited 5 magnetically in order to generate sound waves or is excited by sound waves so as to generate corresponding fluctuating electric currents.

In telephone receivers the vibratory magnetic diaphragm is usually clamped in position on the edge of the casing by means of a screw threaded cap which engages with a corresponding screw threaded portion on the casing. The screw threads on the casing and 10 cap involve either separate thread cutting operations or the molding of the screw threads in corresponding molds. By avoiding the screws, the molds become less expensive and the operation of extracting the 15 molded product is simplified.

The object of the present invention is to provide means for clamping the diaphragm in position independently of the cap or other part so that the casing, cap or other cooperating part need not be provided with screw 20 threads.

According to the invention, a diaphragm is employed which may be of the same or less diameter than the external diameter of the 25 casing, and its edge is held in a clamping ring adapted to hold it over the mouth of the casing. The clamping ring may consist of sheet metal pressed in a jig so as to grip the marginal portion of the diaphragm and 30 provide a depending rim adapted to be pressed over the edge of the casing. In another manner of construction a short cylinder of sheet metal internally of the same diameter as the diaphragm is provided at the 35 top end with V-shaped notches and with cuts in the bottom end so that when the tongues at the top end are pressed flat on the diaphragm they come closely adjacent one another and then alternate parallel sided tongues at the 40 bottom end are pressed flat on to the underside of the diaphragm whilst the remainder are used to grip the side of the casing and may be pressed under a flange or into a groove. In a modification of this construction 45 incisions are made in the cylinder to form tongues to be pressed flat on the underside of the marginal portion of the diaphragm whilst the lower edge of the cylinder is left intact to give additional strength.

With these arrangements the diaphragm is held over the open-end of the casing without the necessity of the cooperation of the cap or other constructional part of the device, and the cap or other part need only make a sliding fit over the edge of the casing or of the clamping member.

The novel features which we believe to be characteristic of our invention are set forth with particularity in the appended claims. Our invention itself, however, will best be understood from reference to the following specification taken in connection with the accompanying drawing in which Fig. 1 is a cross sectional view partly broken away of a sound transmitting device embodying the 55 features of our invention; and Figs. 2 to 6 inclusive are cross sectional views partly broken away of various modifications of our invention. Like reference numerals are employed in the different figures of the drawing 60 to designate similar parts.

In Fig. 1, a diaphragm 11 is shown with its periphery resting against the open end of an instrument casing 12 and it is clamped in this position by means of an annular 65 flanged ring 13, the flat disk portion of which rests upon the outside of the diaphragm, while the lower depending rim is a close fit against the outside of the casing 12. A cover 14 of the instrument, preferably of metal and the depending flange 15 thereof makes a tight fit against the cooperating part of the clamping member 13.

In the modification shown in Fig. 2 the clamping member 13 is provided with an 70 outwardly extending flange 16 against which the end of the flange 15 of the cover 14 rests. The middle portion of the clamping member 13 is raised, as at 17 and terminates in an 75 annular upstanding flange 18 arranged to lie against the cooperating flange 19 on the cover 14.

In the modification shown in Fig. 3 the 80 end of the flange 16 is curled around the end of flange 15, as indicated at 21, and also 85 the end of the flange 19 is curled around the inner portion of the clamping member 13, as indicated at 22.

Referring now to Fig. 4, the clamping member 13 is provided with a number of 90 axial slits in its depending rim portion and the material between each pair of slits is alternately bent upwardly, indicated at 95 23,

against the under side of the diaphragm 11, leaving a number of tongues 24 to engage against the outside of the casing 12. The disk portion of member 13 may be made by 5 providing V-shaped slits and then bending over the material between each slit, as shown at 25.

In the arrangement shown in Fig. 5, the clamping member 13 is arranged to engage 10 the cover 14 externally thereof as indicated at 26, and a downwardly projecting rim 27 is provided on the cover to engage the upper side of the diaphragm.

Fig. 6 shows a modification which differs 15 from Fig. 5 mainly in that the clamping member 13 is shaped to provide a more artistic appearance.

What we claim as new and desire to secure by Letters Patent of the United 20 States, is,—

1. In an acoustic device, a perforated cover having a depending flange, and a flanged ring supported within said cover by frictional engagement with the depending 25 flange.

2. In combination, an acoustic device comprising a flanged cover provided with a central opening extending therethrough, a diaphragm mounted within the cover, and a 30 flanged ring, arranged to support said dia-

phragm and supported within said cover by frictional engagement therewith.

3. In combination, an acoustic device comprising a casing, a diaphragm, and means for supporting said diaphragm comprising 35 a flanged ring supported by frictional engagement with the outer surface of the casing.

4. In an acoustic device, a casing, a diaphragm cooperating with one end of said casing, means adapted to maintain said diaphragm in position on the casing, said means comprising a flanged ring pressed against the outer surface of said casing, and a flanged cover co-operating with said diaphragm and adapted to slidably engage said flanged ring, said cover having a central opening extending therethrough. 45

5. An acoustic device comprising a casing, a diaphragm associated with one end of the casing, frictional means comprising a flanged ring for maintaining the diaphragm in position, and a perforated cover mounted above said diaphragm and adapted to frictionally engage said ring. 50

In witness whereof, we have hereunto set our hands this 19th day of April, 1926.

JOSEPH HUTT.
GEORGE H. BIRD.
